UNITED STATES PATENT OFFICE.

AUGUST SCHAFER, OF EAST COLUMBUS, OHIO.

ANTIBUZZING DEVICE FOR TELEPHONES.

No. 859,464.

Specification of Letters Patent.

Patented July 9, 1907.

Application filed December 24, 1906, Serial No. 349,328.

To all whom it may concern:

Be it known that I, AUGUST SCHAFER, a citizen of the United States, residing at East Columbus, in the county of Franklin and State of Ohio, have invented 5 a certain new and useful Improvement in Antibuzzing Device for Telephones, of which the following is a specification.

The object of this invention is to provide a simple, cheap and effective device for eliminating buzzing in 10 telephone receivers.

In my invention I provide, as will be hereinafter fully explained, a device that can be easily and promptly interposed between the diaphragm and cap ring or ear piece of the receiver, said device operating 15 to deaden, absorb or prevent the creation or transmission of such noises to the ear of the user.

The invention consists in the construction herein-after described and claimed.

In the accompanying drawings in which I have 20 illustrated an embodiment of the invention—Figure 1 is an edge view of the wire netting or screen piece; Fig. 2 is a plan view of the same; Fig. 3 is an edge view of an annulus that may be employed in the construction; Fig. 4 is a plan view of the same; Figs. 5 25 and 6 are edge and sectional views respectively of the concavo-convex disk; Fig. 7 is a plan view of the same; Fig. 8 is an edge view of the several parts assembled and bound together; Fig. 9 is a plan view of the same; Fig. 10 is a view of a fraction of an ordinary telephone 30 receiver showing my device applied thereto, the cap ring or ear piece being in diametrical section, the parts in this view being on a larger scale than in the other views.

The parts of the anti-buzzing device, as above referred to and as shown, are all of circular form and of substantially the same diameter to adapt them to the form of receiver at present in common use, but I know 35 of no reason why they could not be modified in this respect if the form of the receiver required it. The 40 screen part 11 of the device comprises a flat piece of woven metal, preferably steel wire, netting, with a disk 11^a of preferably waxed paper of equal diameter pasted or glued to one side of it. The paper member of the screen piece is coated in its center, as within the 45 circle 11^b, preferably with a thick enamel paint or shellac. 12 designates an annulus preferably of mica, although it might be of metal, paper or other material. 13 designates the concavo-convex piece. This last named piece is preferably of metal, for examples—

aluminium or steel. This concavo-convex piece is 50 covered on both sides, as seen at 13^a and 13^b, with ordinary paper—wrapping paper will do—pasted or glued thereto. The convex side of the paper covering of this disk is coated in its center, as within the circle 13^c, with a thick enamel paint or shellac. These 55 separate parts, as above described, are all assembled together or superposed on each other in the order in which they are shown and as seen in Figs. 8 and 10; and for convenience in handling the parts are bound together at the edges. Small metallic clips 14 secured 60 at different points around the edge of the assembled parts will suffice for this last named purpose. The device as thus constructed is clamped in the telephone receiver between the cap ring or ear piece 15 and the body or handle piece 16 with the wire netting piece 65 lying next the diaphragm of the receiver.

Various modifications in the construction thus shown and described can be made but the best results I believe are attained with constructions as precisely described.

The annulus shown in Figs. 3 and 4 can be entirely omitted but, as before indicated, better results are had when it is included.

I have found by many trials and tests that my device eliminates entirely or largely relieves the buzzing 75 commonly observed by users of telephone receivers, but I am not at present prepared to explain why the device effects this result.

What I claim and desire to secure by Letters Patent is:

1. An anti-buzzing device for telephone receivers comprising essentially in combination, a wire screen, a washer-like device, and a concavo-convex piece, adapted to be placed together and secured in the ear piece of the receiver.

2. An anti-buzzing device for telephone receivers comprising essentially in combination, a wire screen, and a concavo-convex piece, adapted to be placed together and secured in the ear piece of the receiver.

3. An anti-buzzing device for telephone receivers comprising in combination, a woven wire screen and a paper covering added thereto.

4. In an anti-buzzing device for telephone receivers, a wire screen and a paper covering therefor having a painted or shellacked central portion.

5. In an anti-buzzing device for telephone receivers, the combination of a wire screen and a concavo-convex piece having a paper covering added thereto.

6. In an anti-buzzing device for telephone receivers, the combination of a wire screen and a concavo-convex piece having a paper covering added thereto on both sides.

7. In an anti-buzzing device for telephone receivers, the combination of a wire screen and a concavo-convex disk

having a paper covering added thereto, said paper covering having a painted or shellacked center.

8. In an anti-buzzing device for telephone receivers, the combination of a wire screen, and a concavo-convex piece 5 superposed with reference to each other, and means for holding them together.

9. An anti-buzzing device comprising in combination, a metallic disk, a wire screen, and a paper covering added thereto.

10. An anti-buzzing device comprising in combination, a wire screen and a metallic disk superposed one with reference to the other.

11. An anti-buzzing device comprising in combination, a metallic plate, a ring or washer, and a wire screen.

AUGUST SCHAFER.
